UNITED STATES PATENT OFFICE.

JOHN BOYLE, OF NEW YORK, N. Y., ASSIGNOR OF ONE-HALF TO DANIEL T. WILSON, OF NEW YORK, N. Y.

RACK.

No. 886,933.

Specification of Letters Patent.

Patented May 5, 1908.

Application filed May 7, 1907. Serial No. 372,879.

To all whom it may concern:

Be it known that I, JOHN BOYLE, a citizen of the United States, and a resident of the city of New York, borough of Brooklyn, in the county of Kings and State of New York, have invented a new and Improved Rack, of which the following is a full, clear, and exact description.

This invention relates to certain improvements in racks or rails adapted to be secured to the back of a chair, to the wall, or to any other suitable stationary body and serve to support coats, wraps or other garments and the like.

15 The device is so constructed that the rail or rack bar may be held in an extended position ready for use, or may be lowered to a position closely adjacent the chair back or other body to which the device is secured.

20 The rail or rack being adjustable is especially useful in trains, carriages, automobiles, churches, assembly halls, or other places where chairs or seats are placed in front of each other, and where it is desired to remove

25 the wraps and support the same from the back of the chair or seat directly in front.

The rack may be normally left in its lowered position so as not to obstruct the passage in any way, and when it is desired to use the 30 same it may be readily moved to an extended position and firmly support garments.

The device is also adapted for use in houses or offices, and serves to support towels, newspapers, robes, or hangings of any kind, and 35 may be constructed of sufficient strength to support any desired weight.

The invention consists in certain features of construction and combination of parts, all of which will be fully set forth hereinafter 40 and particularly pointed out in the claims.

Reference is to be had to the accompanying drawings, forming a part of this specification, and in which similar characters of reference indicate corresponding parts in all the figures, and in which

45 Figure 1 is a perspective view of my improved rack in its extended position; Fig. 2 is a front elevation of the rack in its lowered or depending position; and Fig. 3 is a sectional detail showing the construction of the trunnion and bearing therefor.

In the specific form of my invention illustrated in the accompanying drawings, I provide two bearings 10 and 11 in alinement 50 with each other and adapted to be rigidly

secured to any suitable support, as, for instance, the back of a chair. The bearings have preferably cast integral therewith flanges 12 having screw holes by which the bearings may be readily secured in place. 60 In the drawings I have illustrated a bar 13 as constituting the stationary support, and the bearings as being provided with flanges 14 screwed thereto, although it is evident that the flanges may be of any form whatsoever to adapt them to the body in connection with which my improved rack is employed. Each of the bearings is closed at the inner end and open at the outer end, and within the bearings are mounted the trunnions 15 and 16 of the main garment supporting rack 17.

65 The rack may be of any form desired, but is preferably straight throughout the major portion of its length and provided with 70 curved portions 18 connecting it to the trunnions 15 and 16. The two trunnions are in alinement with each other and face inwardly from the curved portions 18.

75 To hold the rack in its extended or its depending position, I provide both of the bearings 10 and 11 with double bayonet slots 19. These slots are substantially U-shaped and the two parallel portions of each slot extend lengthwise of the bearings while the cross 80 portion runs circumferentially. Each of the trunnions is provided with a pin 20 extending radially therefrom and through the bayonet slot. The trunnions are longitudinally 85 movable in the bearings and the pins may be caused to travel throughout the entire length of their respective slots by moving the trunnions longitudinally and rotating the same. For holding the pins in the ends of the slots, I provide one of the bearings, 90 preferably the bearing 10, with a coil spring 21 within the bearing and engaging with the closed end thereof and with the end of the corresponding trunnion 15, as is clearly 95 illustrated in Fig. 3.

100 In Fig. 1 the rack is illustrated in its outer or extended position and with the same securely locked in place by the engagement of the pins in the ends of the slots. In order to lower the rack bar the entire bar is moved 105 longitudinally by pressing on the end of the trunnion 15, and when the pin has been moved a sufficient distance the rack may be moved to a position closely adjacent the chair back or other supporting body, and 110

upon releasing the rack the pin enters the lower horizontally disposed portion of the slot and securely and rigidly holds the rack in its lowered position.

5 Having thus described my invention, I claim as new and desire to secure by Letters Patent:

1. A rack, comprising two stationary bearings in alinement with each other, a rack 10 bar having trunnions rigid therewith and in alinement with each other, said trunnions being rotatably and longitudinally movable within said bearings, one of said bearings being provided with a slot having two longitudinally-extending portions and the corresponding trunnion having a radially-extending projection adapted to enter either of said two longitudinally-extending portions to hold the rack in either of two positions, and a 15 spring in engagement with one of said bearings and the corresponding trunnion for holding the projection within one of the longitudinally-extending portions of the slot.

2. A rack, comprising two stationary 20 bearings in alinement with each other, a rack bar having trunnions in alinement with each other and substantially parallel to said rack bar but out of alinement therewith, said trunnions being rotatably and longitudinally

movable within said bearings, and said co-acting trunnions and bearings having bayonet joint connections for holding the rack in either one of two positions, and a coil spring within one of said bearings and in engagement with the end of the corresponding trunnion for holding the bayonet connections in the desired relationship.

3. A rack, comprising two stationary bearings in alinement with each other, a rack bar having trunnions rigid therewith and in alinement with each other, said trunnions being rotatably and longitudinally movable within said bearings, said bearings having double bayonet slots, and said trunnions having radially extending pins in engagement with said slots to hold the rack in either one of two positions, and a coil spring within one of said bearings and in engagement with the end of the corresponding trunnion for holding the pin in either extremity of the bayonet slot.

In testimony whereof I have signed my name to this specification in the presence of two subscribing witnesses.

JOHN BOYLE.
